*Primary Examiner—Janice E. Seeger
Attorney, Agent, or Firm—Herbert Dubno***[57] CLAIM**

The ornamental design for a side-mounted writing table, as shown and described.

DESCRIPTION

FIG. 1 is a bottom front perspective view of a side-mounted writing table, showing my new design, the broken lines being for environmental purposes only and forming no part of the claimed design;

FIG. 2 is a left-side elevational view thereof;

FIG. 3 is a right-side elevational view thereof;

FIG. 4 is a top rear perspective view thereof;

FIG. 5 is a top plan view thereof;

FIG. 6 is a bottom plan view thereof;

FIG. 7 is a view thereof similar to FIG. 1 showing the surface of the table folded down;

FIG. 8 is a left-side elevational view thereof;

FIG. 9 is a right-side elevational view thereof;

FIG. 10 is a rear view thereof;

FIG. 11 is a top view thereof; and,

FIG. 12 is a bottom view thereof.
